[57] CLAIM

The ornamental design for a microwave oven, as shown and described.

DESCRIPTION

FIG. 1 is a front elevational view of a microwave oven showing our new design; and

FIG. 2 is a top plan view thereof; and

FIG. 3 is a side elevational view thereof; and

FIG. 4 is a bottom plan view thereof; and

FIG. 5 is a back elevational view thereof.
The side of the oven which is not shown is a mirror image of the side disclosed in FIG. 3.

*FIG. 1**FIG. 2**FIG. 3**FIG. 4*

FIG. 5
